GAS RANGE

Carl E. Methudy, St. Louis, Mo., assignor, by
mesne assignments, to The Cleveland Trust
Company, Cleveland, Ohio, a corporation of
Ohio

Application October 2, 1929, Serial No. 396,724

1 Claim. (Cl. 158—117.1)

This invention relates to gas ranges.

An object of the invention is to provide a construction and arrangement in a gas range whereby the gas from the gas supply pipe is conducted 5 to the gas manifold of the range through a valve which controls passage of gas from the supply pipe to a pilot light device and also to the manifold, which supplies gas to the several burners of the gas range.

10 Another object of the invention is to provide the construction and arrangement of the type and character mentioned having thermostatic members in connection with and controlling the valve that controls the passage of gas to the pilot light 15 burner and to the manifold whereby said valve will be automatically closed when the flame at the pilot light burner becomes extinguished and the thermostatic device becomes unheated.

Another object of the invention is to provide a 20 gas range embodying the improved construction and arrangement of parts herein disclosed, reference being made to the accompanying drawings, in which—

Fig. 1 is a plan view of a portion of the gas 25 range showing a cluster of gas burners and a pilot light burner and valve therefor controlling the passage of gas to the manifold of the range.

Fig. 2 is an enlarged vertical sectional view of the pilot light device and valve approximately on the line 2—2 of Fig. 1.

30 In the embodiment of the invention shown, a cluster of gas burners 1 is assembled in appropriate relationship within a burner box frame 2. The oven of the range is equipped with a 35 gas burner 3 having a gas inlet device 4. The burners 1 have gas inlet devices 5.

The main gas supply pipe 6 is mounted in the support 7 in connection with the burner box frame and has a pipe extension 8 extending forwardly toward the center of the cluster of 40 burners 1 to connection with a valve housing which encloses a valve that controls passage of gas to the pilot light burner and also controls the passage of gas to the manifold 9 of the 45 range.

The manifold 9 of the range is located on the 50 inside of the burner box frame below the upper inwardly extended portion 10 of said burner box frame. A pipe 11 opens into the manifold 9 for conducting gas to said manifold from the housing provided in connection with the pilot light burner. Valves 12 control the discharge of gas from the 55 manifold 9 into the various gas inlet devices 5 for the burners 1, and into a tube for conducting

gas to the gas inlet device 4 leading to the oven burner 3.

A housing 14 for enclosing the flame of the pilot light burner is located near the center of the cluster of burners 1 and has tubular arms 15 open throughout their length and extending toward and terminating adjacent to the burners 1, so that gas being discharged from said burners 1 will enter the tubes 15 and be conducted thereby to the housing 14 and therein ignited by the pilot light flame. As a result of the ignition of the gas in the housing 14 and tubes 15, a pressure wave of combustion is formed in said tubes 15 with the result that the gas being discharged from the tubes of the burners 1 is 10 ignited. A tube 16 leads to the burner 3 for the same purpose; and a tube 17 may be provided for a special burner 1a.

The pipe 8 has communication with the pipe 11 through a valve housing. The valve housing comprises a bottom wall 18 and a cylindrical wall 19 rising from the wall 18. The walls 18 and 19 form an enclosure or housing having at one end a tubular internally threaded lateral extension 20 forming a gas receiving chamber 21 and screwed on to the end of the pipe 8. The opposite side of the valve housing has a laterally extended internally threaded tubular portion 22 into which the end of the pipe 11 is screwed.

Within the valve housing an annular wall 23 rises from integral union with the bottom wall 18 and encloses a space 24 to which gas is admitted from the receiving chamber 21 through an inlet 25. The wall 19 has a downward extension 26 curving to integral union with the upper portion of the wall 23, so that it is impossible for the gas to pass from the receiving chamber 21 otherwise than through the port 25 and through the enclosed space 24, and thence upwardly across the valve seat 27 on the upper edge of the wall 23.

A valve 28 is attached to a support 29 mounted and guided in the space formed by the wall 19 and is movable from and to position on the valve seat 27. When the valve 28 is seated on the valve seat 27 it is impossible for gas to pass from the pipe 8 to the pipe 11; and when the valve 28 is raised from the valve seat 27 the gas may freely pass from the pipe 8 to the pipe 11 and thence to the manifold 9. A retractile spring actuator 30 is connected with the projection 31 from the valve support 29 and with a rigid member 32 and operates to close the valve.

When the valve 28 is raised and held away from the valve seat 27 the gas may pass around the support 29 into the chamber 33 enclosed by the

wall 19 above the support 29. A leak proof construction is provided, comprising a diaphragm 34 having its outer edge clamped in connection with the wall 19 by a clamp 35. A burner jet tube 36 extends for sliding movements in a boss 37 in connection with the clamp 35 and opens into the chamber 33 through a fitting 38 having ports 39 therein. These ports 39 form communication from the chamber 33 to the tubular burner member 36 so that gas may pass from said chamber 33 to the burner tip 40. A thermostatic member 41 is attached to the burner tube 36 and is arranged to be engaged on the shoulder 42 in connection with the boss 37 when the burner tube 36 is raised to open the valve 28. The fitting 38 has swivel connection 43 with the valve support 29 so that said valve support will be operated by the tube 36, and vice versa. Thus, when the tube 36 is moved, which may be conveniently done by manually engaging a projection 44, the valve 28 may be opened and the thermostatic device 41 will engage its lower end upon the shoulder 42. This will permit gas to pass to the burner tip 40 and also outwardly through gas outlet openings 45. When this gas is ignited the thermostatic device 41 becomes heated and moves outwardly away from and out of engagement with the shoulder 42 permitting the spring 30 to draw the valve 28 toward closed position.

Another thermostatic device 46 is provided in connection with the burner tube 36 and is of shorter length than the thermostatic device 41 and is arranged to operate oppositely. That is to say, when the thermostatic device 46 becomes heated it bends inwardly to position to engage upon the shoulder 42. And when the thermostatic device 46 becomes cooled it moves and bends outwardly out of engagement with the shoulder 42.

Accordingly, the operation is in this manner: The valve 24 is opened by manually engaging the projection 44 and moving the tube 36 upwardly. The tube 36 moves the valve 28 to open position. Gas then passes into the chamber 33 and thence to the burner tip 40 and gas outlets 45. When the tube 36 is moved upwardly the lower end of the thermostatic device 41 snaps over the shoulder 42 and holds the tube 36 in its uppermost position, and the gas passing through the burner tip 40 and through the gas outlet openings 45 is ignited. Both thermostatic devices 41 and 46 are, therefore, heated, with the result that the thermostatic device 41 is moved out of engagement with the shoulder 42 and the spring 30 then acts to move the valve 28 and other connected parts downwardly until stopped by engagement of the thermostatic device 46 upon the shoulder 42. In this way the valve will be held open until the flames at the openings 45 become extinguished and the thermostatic device 46 becomes cooled. When the thermostatic device 46 becomes cooled it bends and moves outwardly out of engagement with the shoulder 42; and then the spring 30 acts quickly to close the valve 28 and thereby prevent passage of any gas to the manifold 9 or through the pilot light device.

From the foregoing it is apparent that my invention obtains all of its intended objects and purposes efficiently and satisfactorily. The construction and arrangement may be varied widely within the scope of equivalent limits without departure from the nature and principle of the invention. I do not restrict myself unessentially but what I claim and desire to secure by Letters Patent is:

In combination, a gas range having a plurality of burners, a pilot light casing, tubes branching from said pilot light casing to each of said burners, said pilot light casing and said tubes forming an integrated, rigid, removable structure normally supported by said burners, a pilot burner separate from said pilot light casing and unattached thereto, said pilot burner being constructed and arranged to maintain a flame within said casing, and a thermostatically controlled valve controlling the gas supply of all said burners in accordance with the condition of the pilot burner.

CARL E. METHUDY.
